CLAIM

The ornamental design for a display screen or portion thereof with graphical user interface, as shown and described.

DESCRIPTION

The FIGURE is a front view of a display screen or portion thereof with graphical user interface showing the new design.

The outermost broken lines indicate unclaimed portions of the article and form no part of the claimed design. The innermost broken lines indicate unclaimed portions of the graphical user interface and form no part of the claimed design.

1 Claim, 1 Drawing Sheet
